CLAIM

The ornamental design for a vacuum drainage storage bottle, as shown and described.

DESCRIPTION

FIG. 1 is top perspective view of a vacuum drainage storage bottle in a disconnected configuration.

FIG. 2 is a top perspective view of the vacuum drainage storage bottle of FIG. 1 in a connected configuration.

FIG. 3 is a top perspective view of the VAcuum drainage storage bottle of FIG. 1.

FIG. 4 is a bottom perspective view thereof.

FIG. 5 is a front view thereof.

FIG. 6 is a rear view thereof.

FIG. 7 is a top view thereof.

FIG. 8 is a bottom view thereof.

FIG. 9 is a left side view thereof, the right side being a mirror image.

FIG. 10 is a cross-sectional view thereof taken from line 10-10 in FIG. 5; and,

FIG. 11 is a cross-sectional view thereof taken from line 11-11 in FIG. 6.

The broken lines in the drawings depict environmental subject matter and form no part of the claimed design.
